UNITED STATES PATENT OFFICE.

THORALF SCHRÖDER-NIELSEN, OF HORTEN, NORWAY, ASSIGNOR TO CHRISTOFFER HANNEVIG AND HANNEVIG BROTHERS, A/S, OF CHRISTIANIA, NORWAY.

BOAT-DAVIT.

1,312,272.

Specification of Letters Patent.

Patented Aug. 5, 1919.

Application filed March 27, 1918. Serial No. 224,992.

To all whom it may concern:

Be it known that I, THORALF SCHRÖDER-NIELSEN, a subject of the King of Norway, residing at Horten, in the Kingdom of Norway, have invented certain new and useful Improvements in Boat-Davits; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The present invention relates to boat-davits of the kind, which are mounted to swing on an inclined axis in order that the boat may be easily swung out, even when the ship has a heavy list or is rolling on high sea.

According to the present invention the angle of the davit axis and the form of the davit are so adjusted that the boat rib is brought to the level of the ship's deck, when the boat is swung out, whereby the boat may conveniently be manned without lowering the same and without being hindered by the rolling of the ship or by the ship having a list. Further the davit is so formed that the distance from the fastening point of the boat to the nearest part of the ship, when the boat is swung out, is longer than from the fastening point of the boat to the lowest point of the same.

By this arrangement the boat when being lowered can not strike the ship's side and be molested thereby, even when the ship is rolling very much or has a heavy list.

On the drawings Figure 1 is an end view of the davit and its operating girder. Fig. 2 is a side view of the same. Fig. 3 is a diagrammatical view of the boat and davits in different positions as seen from above. Fig. 4 is a diagrammatical view of the girder in position for steadyng the boat when the same is swung out.

The davit 1 is supported in sockets 2-3 in such a manner, that the axis of the davit forms an angle of about 60 degrees with the deck. At the top of socket 2 the davit is provided with a ring 4, having a stopper which serves to prevent the movement of the davit in one direction.

The two davits 1 are connected at their upper ends by means of a bar or rod 5,

which is mounted on trunnions 6-7 at the end of each davit and secured in position by means of a pin or other suitable device. Said bar 5 which may suitably consist of an I-beam, serves to steady the davits and to support the blocks 8-9 by which the boat is lowered and raised. Also by means of this connecting bar the movement of both davits are made synchronous. In order to keep the davit in its inner or outer position and to perform the swinging movement of the davit, a forked cable 14 is provided, which is fastened with its two ends to the bar 5, one part of the cable fork being fastened to one end of bar 5, while the other end of the fork is fastened to bar 5 at a point immediately in front of block 8.

At the middle the forked cable 14 is connected to tackles 10-11, the standing blocks of which are fastened to a support 28 near the middle on the ship's deck. Said support 28 may also serve as support for the cable belonging to the boat at the opposite side of the ship. The distance between the standing blocks at the support may conveniently be made a little larger than the radius of the davit.

The support is so placed that the tackle 11 is perpendicular to the bar 5, when the latter is in its middle position (indicated on Fig. 3 in point- and dotted line). When the davit is swung into its inner position as indicated in full lines on Fig. 3 one member of the cables 14 should be in line with tackle 10.

The tackle 11 during the swinging out of the davit should take the stress from the tackle 10 some time before the davit bar 5 passes its middle position, when the fall of the tackle 11 is not slackened. When the boat is hauled in or when the ship is rolling heavily (e. g., more than 30 degrees) the davit is kept in its outer position by engaging the cable with two hooks 29, fastened to the deck and hauling taut the tackles 10-11.

The boat in its inner position rests on chocks 15-16, pivoted on trunnions 17-18, fastened to the deck. At a point 19, just below the keel of the boat, the chocks are provided with pivoted rods 20-21, the lower ends of which are curved and can slide on the deck. Said rods 20 and 21 are connected with each other by means of wire 24 and tackle 22 in such a manner, that the chocks, when said tackle is slackened, are

swung in an outwardly and downwardly direction by means of the weight of the boat. Wires 26—27 prevent the chocks from swinging too much in the opposite direction.

The davit is operated in the following manner:

Swinging out the davit.

- 10 The tackle 10 is slackened until the stress is taken up by the tackle 11. The tackle 11 is slackened until the davit has reached its outermost position. The tackle 10 is not used in this part of the operation.
- 15 If the ship's list exceeds 30 degrees the boat is pushed out and maintained in its outer position by means of hooks 29 in the manner described.

Swinging in the davit.

- 20 The tackle 11 is hauled until bar 5 has passed its middle position, whereupon the hauling proceeds by means of the tackle 10. (When the davit has reached its inner position both tackles are hauled taut and fastened.)

I claim:

1. A boat davit mounted to turn in inclined sockets, the angle of the socket and 30 the form of the davit being so proportioned that the distance from the davit jib to the nearest part of the ship, when the davit is swung out, is longer than from the davit jib to the keel of the life boat.
- 35 2. A boat davit mounted to turn in inclined sockets, the angle of the socket and the form of the davit being so proportioned that the boat rib is lowered approximately to the level of the ship's deck, when the 40 davits are swung out, the davit jibs being connected by means of a rod or bar, the ends of which are mounted on trunnions at the top of each jib.

- 45 3. A boat davit mounted to turn in inclined sockets, the angle of the socket and the form of the davit being so proportioned that the boat rib is lowered approximately to the level of the ship's deck, when the

davits are swung out, the davit jibs being connected by means of a rod or bar, the 50 ends of which are mounted on trunnions at the top of each jib, a forked girder being connected with its ends to two points of said bar and at the middle to two tackles fastened some distance apart to a stationary part of 55 the ship.

4. A boat davit mounted to turn in inclined sockets, the angle of the socket and the form of the davit being so proportioned, that the boat rib is lowered approximately 60 to the level of the ship's deck, when the davits are swung out, the davit jibs being connected by means of a rod or bar, the ends of which are mounted on trunnions at the top of each jib, a forked girder being connected with its ends to two points of said 65 bar and at the middle to two tackles, the standing blocks of which are fastened to a stationary part of the ship at points some distance apart on a line parallel to the said 70 bar.

5. A boat davit mounted to turn in inclined sockets, the angle of the socket and the form of the davit being so proportioned that the boat rib is lowered approximately 75 to the level of the ship's deck, when the davits are swung out, the davit jibs being connected by means of a rod or bar, the ends of which are mounted on trunnions at the top of each jib, a forked girder being connected with its ends to two points of said 80 bar and at the middle to two tackles, the standing blocks of which are fastened to a stationary part of the ship in such a manner, that one tackle is perpendicular on said bar, 85 when the boat is in its middle position, while the other tackle is in line with one part of the forked girder, when the davits are in their inner position.

In testimony that I claim the foregoing 90 as my invention, I have signed my name in presence of two subscribing witnesses:

THORALF SCHRÖDER-NIELSEN.

Witnesses:

C. FABRICIUS HANSEN,
M. W. KAHN.
